ALBERT KOCH ANDRIANO, OF SAN FRANCISCO, CALIFORNIA, ASSIGNOR TO DIRECT-LINE GENERAL TELEPHONE COMPANY, OF SAN FRANCISCO, CALIFORNIA, A CORPORATION.

SECRET-SERVICE-TELEPHONE CIRCUITS AND SWITCHING MECHANISM.

986,889.

Specification of Letters Patent. Patented Mar. 14, 1911.

Application filed March 15, 1905. Serial No. 250,154.

To all whom it may concern:

Be it known that I, ALBERT KOCH ANDRIANO, a citizen of the United States, residing in the city and county of San Francisco and State of California, have invented new and useful Improvements in Secret-Service-Telephone Circuits and Switching Mechanism, of which the following is a specification.

10 This invention relates to switch-devices and circuit-controlling means connected with or applicable to telephone systems of the kind in which each telephone, or "station", is provided with means for obtaining direct communication with another station without depending on a central exchange.

One object of the invention is to simplify the construction of the switching and connecting means in telephone systems of this character; to enlarge the capacity of the system without correspondingly increasing the mechanism for setting up and completing the circuits; and to render more positive and certain the production and maintenance of a closed circuit and secret communication between two stations as long as they are in use.

To these and other ends and objects the present improvements embrace a line-selecting switch and circuit-controlling means of improved construction, in combination with the conductors of the talking and ringing-circuits, through the medium of which the completion of a circuit for talking between two stations is controlled and made to depend on a ringing-circuit being formed and a current transmitted over the line to the bell at the called station. The following description explains at length the nature of these improvements, and the manner in which I proceed to apply and carry out the same; reference being had in this description to the accompanying drawings in which:—

Figure 1 is a front-elevation of a switch-box of the kind generally termed a wall-telephone, constructed in accordance with this invention and containing the switching-mechanism and circuit-controlling device. The cover or front that incloses the mechanism both of the switch and the controlling-device is partly broken away to disclose the parts within. Fig. 2 is a front-view of the

front-plate of the switch-box removed from the case, showing the parts of the line-switch and some of the circuit-closing contacts carried by the plate. Some parts of the line-switch are broken away to uncover parts beneath. Fig. 3 is a top-view of the lower set of stationary-contacts that are terminals of the lines, and the two movable-contacts of the switch; the upper set of stationary-contacts with which one of the movable-contacts co-operates to control the operating-circuit of the circuit-controller being omitted from this figure. Fig. 4 is a section through the line-contacts on the line $x-x$ Fig. 3. Fig. 5 is a top-view in detail of the upper set of stationary contacts removed from above the line-contacts. Fig. 5^a is a section taken diametrically through Fig. 5 on the line $y-y$. Fig. 6 is a side-view of the stationary-contacts and the movable-contacts seen in Fig. 3. Fig. 7 is a front-view of the back-panel, or base, of the switch-box, and Fig. 7^a is a front-view of the front-panel and cover detached and removed from the base. Figs. 8, 9 and 10 are details of the electrically operated circuit-controller; Fig. 8 being a front-view; Fig. 9 a detail of the movable-contact and its rocking-lever, and the armatures that actuate it; and Fig. 10, a top-view of the stationary contacts and the movable-contact. Fig. 11 is a diagrammatic representation of four stations set up and connected in one system in accordance with my invention, and showing each station provided with the switching and circuit-controlling devices.

In telephone systems of this character wherein the stations are connected by separate conductors having terminals in the switching-devices at all the stations, any increase in the number of telephones or stations necessarily involves the addition of a considerable number of lines or conductors to be connected into the switching-device and the mechanism of the switch-box at every station, and a corresponding increase in the labor and expense of setting up and connecting each station for operation, and in the work of disconnecting a switch-box and replacing it by a new one when repairs are required. The improvements in the construction of the present switch-box facilitate the coupling or making connections of the wires and other conductors with the

parts inclosed in or mounted on the switch-box, such as the lines that "run out" of the station to the bell-battery and the remaining stations in the system. They also prevent 5 the liability of making wrong connections in removing and replacing a switch-box, or in substituting a new box. This part of the invention consists of a back-panel, or base A, which becomes the stationary part when it is 10 fixed in a permanent manner to the wall, and a detachable front composed of panel B and front-plate b on which the switch and other circuit-closing parts are fixed. These 15 two parts—the back-panel A and the front panel B are secured together by means of a row of interlocking catches fixed along on each side of the panel, and composed of pins 7 fixed at intervals apart along the sides of one panel, and a corresponding number of 20 spaced hooks 8 along the sides of the other panel. The pins 7 are fixed in metallic strips 7^a, to the ends of which the ends of the conducting-wires α α α are tied, or coupled, in such manner that each pin 7 forms the 25 terminal of a conductor on the back-panel. Each pin and the strip in metallic connection with it on the back-panel is insulated from the others by being fixed in a block of insulating material k^1 on the side of the 30 panel. The pins are spaced at somewhat greater distance apart than the hooks 8 on the other panel, so as to allow the hooks to be placed between the pins; and the two 35 panels are readily fastened together by setting one panel against the other and giving the front panel a short movement in a plane with the back-panel, after the hooks are aligned with the pins. The hooks 8 are formed on the ends of metal strips 8^a having 40 eyes at the opposite ends for connecting the conductors to the strips in the usual way. By using a screw for the part 7, the hook 8 that forms the other part of the coupling can be drawn in close metallic contact with 45 the other metallic strip 7^a after the two are interlocked. This insures a positive electrical connection between the two parts of the coupling by screwing up the pins 7 which are situated outside the inclosing 50 cover d, where they can be reached and turned with a screwdriver. The parts on the front-plate that require to be insulated are fastened to backing-blocks, or strips of insulation, secured to the plate b behind openings b^1 b^2 b^3 cut in the plate to expose the insulation, as seen in Figs. 1, 2 and 3. In 55 setting up this switch-box the various lines and conductors to be carried into or out from the box are distributed among the terminal strips 7^a along the sides of the back and are then permanently fastened to their respective strips. When once attached to the back-panel the wires need not be disturbed, and the back-panel may remain permanently 60 fixed in position wherever it may be placed

for use. In addition to these couplings 7—8, the present switch-box is provided with an additional set of couplings 7^b 8^b for connecting the circuit-controlling device, which, for greater convenience and also for reducing 70 the dimensions of the switch-box, I have arranged in a separate case detachable from the box. A box thus constructed is of great advantage in systems of this character, particularly where the large number of stations 75 require the running and coupling of many lines and wires at every station. It practically eliminates making wrong connections in wiring and installing a switch-box, and greatly reduces the time and labor involved 80 in removing one box and setting another.

The construction and operation of the line-switching mechanism will be best described by reference to Figs. 2, 3, 4, 5, 5^a and 6. The stationary contacts 2 in the larger circle 85 represent the terminals of the home-lines of all the stations excepting the one individual to the switch itself, which in a system of this character has no contact-terminal in the switch, but is normally connected with 90 or into its own primary-circuit through a circuit-controlling device to be hereafter explained. The continuous contact-ring 3 within the circle of these contacts forms the terminal at the switch of a conductor 3^a connected to the movable-stop 12 of the ringing-key. The ring 3 is connected into the stationary contacts singly by the movable-member C on the rotatable post g, to which the member is fixed. One arm 4 of the switch 100 C makes contact with the line-contacts 2, and another arm 5 setting always against the surface of the ring 3 puts the ring 3 in metallic connection with that one of the contacts 2 on which the arm 4 is placed. Connecting a contact 2 with the ring 3, through the switch 4—5 brings the particular line of 105 which that contact is the terminal in circuit with the movable-stop 12 of the ringing-key, with the effect to make the selected line form 110 one side of the calling-circuit in addition to its function of constituting one side of the talking-circuit. In that side of the local circuit with which the selected line is connected by setting the switch 4—5, is located 115 the mechanism designated as the circuit-controller, consisting essentially of an oscillating circuit-closing arm placed between two series of contact-stops that make and break 120 connection on the one hand between the primary-circuit and its own line, and, on the other, between the primary-circuit and the line of the station selected through the switch. The adjustment of the oscillating-member is effected electrically by means of 125 two electro-magnets connected into the switching-mechanism in such manner that on the completion of a normal ringing-circuit with another selected station a current 130 will be caused to flow through one magnet

as the ringing-key is closed; and by the operation of calling up the opposite station the oscillating member of the circuit-controller at the ringing-station will simultaneously 5 separate the primary-circuit at the ringing-station from its own line and connect it with the selected line running to the opposite station. A current through the other magnet, on the other hand, will have 10 the effect to set the oscillating-member to the opposite position and thereby restore the primary-circuit to its own line; and this second magnet is connected in open circuit with the ringing-battery in such manner 15 through the additional circuit making and breaking devices in the line-switch, that the second magnet is inoperative while the line-switch is resting on a main-line terminal and the circuit is completed through it with 20 another station; but a circuit through the magnet last mentioned will be completed if the line-switch 4—5 be moved, with the effect to energize that magnet and by its action on the oscillating member of the circuit-controller 25 throw the latter into position to break connection of the primary-circuit with the selected line and place the station back again on its home-line. The movable member 60—61 of the line-switch acting in conjunction 30 with the contact-plates or rings 63—64 closes the battery *w* on the resetting magnet at such time, because the movable contacts 4—5, 60—61 are mounted on the same pivot and also rigidly connected to the 35 same insulating-piece.

The following construction and arrangement of the circuits and circuit-closing means is employed to prevent the switch from being moved without breaking the connection 40 and throwing the primary-circuit back upon its own line:—The switching device is provided with an additional contact-piece having two arms 60—61, fixed on or carried by the movable member *C*, and a set of supplemental contacts consisting of a contact-ring 45 63 and a series of contact-stops 6 arranged in a circle over and concentric with the line-contacts 2. The longer arm 60 moving in contact with the stationary stops 6, and the 50 shorter arm being at all times in contact with the ring 63, a metallic connection is established between that ring and any one of the stops 6 that the supplemental-switch may touch in its movement around the center *g*. The stops 6 are all in metallic connection with one another through the ring 55 64 with which they are formed integrally, and the ring is connected into the home-line through a conductor 33—33^a. The rings 60 63—64 are fixed to the underside of an insulating plate formed of a block of fiber *k*⁴, and the block is fastened in place over the line-contacts and ring 3 of the main switch by spacing washers or short pillars *i* and ears 65 *k*⁵ on the block *k*⁴ through which screws *k*⁶

take into the bed-plate *k* beneath. The ring 63 fastened to the underside of the same block is insulated by that part from the contacts 6, and is connected by a conductor 40^a into the wire 40 of the bell-circuit. Intermediate stops 65 in the same circle, but having no connection electrically with any part or conductor, separate the line-stops 6 in this upper series of contacts in such manner, that they form a support for the movable 70 arm or member 60 as it moves around the circle. The two movable-contacts 4—60 are fixed on the switch-piece *C* in such position with reference to the stationary contacts in the upper and lower sets that the arm 60 75 will rest on one of the blank-stops 65 when the arm 4 is placed on one of the line-contacts 2. In such position the circuit will be formed through the setting-magnet 50 by means of the connection³³ the stops 12—29 of 80 the ringing-key and the conductors 39—42 and the arm 13 of the circuit-controller. But if the switch-piece be moved off the line-contact to which it has been set the arm 60 85 will be brought in contact with the ring 64 90 at one of the points 6 and the two contacts 60 and 61 will close connection between the rings 63—64, and a current will pass over the circuit formed of the conductors 33^a 95 33 and 37 in which the other magnet 51 of the controller is situated, provided the setting-magnet 50 has previously been energized and the circuit-controller operated. By the movement of the switch-piece off a line-contact therefore the magnet 51 will be 100 energized and the arm 13 will be restored to its normal position against the contact 19 on the right ready for another call. When the line-switch is properly set for operation, and the ringing-key is closed, the magnet 50 will 105 receive current, and attracting the armature 28 it acts to move the oscillating member 13 from right to left on its pivot 25 by attracting the armature-piece 28 on the end of the rocking-lever 26, and throwing that piece 110 over from left to right. The lever 26 turns on a pivot 27 and is loosely connected to the lower end of the oscillating member 13.

Between the movable-stop 12 of the ringing-key and the circuit-controller is placed 115 a circuit-closer composed of contact-springs 39^a 42^a controlled by the telephone-hook in such manner that the circuit-controller at the calling-station and the bell at the called or distant station will be operated only after 120 the receiver has been removed from the hook. The object of controlling the operating-circuit in this manner is to prevent the user from establishing communication with another station without first taking his receiver from the hook, and to restore a telephone to the line when the receiver is hung up. Under the attraction of the magnet 50 125 the circuit-closer 13 is moved from its position against the contact-stops 15, 16, 19 on 130

the right, to the opposite position against the stops 17, 18, 20, 21, 22 on the left; thus separating the primary-circuit conductor 35 from the line 37 and connecting through 5 the contacts 17—18 the conductor 35 into the line 43 running to the front-stop 10 at the ringing-key. By the same movement of the circuit-closer produced by the magnet 50 the second magnet 51 of the circuit-controller 10 is brought into circuit with one side of the battery *w* through the stops 21—22 and the conductors 46—*v*¹; and is also connected through the conductors 37—33 and 33^a with the outer one 64 of two contact 15 plates 63—64 on the line-switch, at which point the circuit that includes the magnet 51 is opened and closed by the movable-contact 60—61, as already described. It will be seen, therefore, that the magnet 50 20 in this circuit-closer operates to set the arm 13 to the left, or in the position to connect the instrument of the station to the line-switch for use; and the other magnet 51 when energized acts to return the arm 13 to 25 its initial position against the stops 15—16—19, in which it breaks the connection between the primary-circuit and the lines of the other stations and restores it to the line individual to the station ready for being 30 called from another station.

The construction and operation of the circuit-controlling devices will be described more particularly with reference to Figs. 1, 3, 9, 10 and the diagram Fig. 11. The contacts 35 stops located on the right side of the arm 13 consist of the stop 15, forming the terminal of one end of the conductor 35 of the primary-circuit, and the two stops 16—19, one being the terminal of the conductor 37 carried to that point from the home-line 33, and the remaining contact 19 the terminal of a conductor 45 in which is included the coils of the magnet 50; conductor 45 is connected permanently into one 40 side of the ringing-battery circuit composed of the lines *v*¹ *v*². The contacts composing the group on the opposite side of the center 45 consist of two stops 17—18 that make and break connection at that point between the conductors 35—43 in the primary-circuit, and the stops 20, 21, 22 that control the connection between the conductor 45 and the coil of the magnet 51. At the points 21—22 connection between one side of the ringing-battery and the line-selecting switch is made 50 and broken according as the arm 13 is set against or is moved away from the contacts 21—22. The upper end of the arm 13 is provided with contact-stops 23—24, located on opposite sides of the arm and insulated from each other, as seen in Fig. 11; and the arm itself is utilized also for a conductor by placing the stationary stops 19—20 in position to make metallic contact with it. 60

65 This function of the arm as a conducting

element or portion of the circuit will be explained hereafter. As the magnets 50—51 act singly to set the arm 13 alternately to the left and the right on its pivot 25 by being connected in circuit with the ringing-battery, the magnet 50 is so arranged that by the act of calling up the opposite station, after having set the line switch, the arm 13 will be thrown over to the left—as represented in station No. 1 of the diagram Fig. 11— 70 and the local-circuit will be closed at the points 17 and 18, 20—21—22. But in moving to that position from the opposite side, the arm 13 opens the local circuit at 15, 16, 19 thereby disconnecting the primary-circuit 80 from its own home-line at 15—16. By touching the opposite contacts the arm 13 closes the primary-circuit on the home-line of the other station over the conductor 43 and through the stops 10—12 of the ringing-key, and thence through the contact 4 of the line-switch to the home-line of the required station. In its normal position the controller 13 rests against the stops 15—16—19, closing the break at 15—16 and 90 connecting one side of the coil of the magnet 50 to the back-stop 29 of the ringing-key through the conductor 45, the contact 19, the arm 13, and thence through the connections 42 and 39. The circuit with the ringing-battery *w* will be completed then at the instant that the movable-stop 12 of the ringing-key is caused to touch the back-stop 29. It will be seen that the magnet 50 becomes 100 energized at the same time that the bell at the opposite station is rung; because the circuit then being closed at 12—29 the current will flow from one side of the ringing-battery over the conductor *v*¹, the connection 45 at the ringing-station and through the coil of magnet 50 to the arm 13; and that part being in its normal position against the stop 19 the circuit is carried through the arm and its operating lever 26, and thence through the connections 42—39 to the ringing-key; 110 the circuit being closed at the springs 39^a 42^a when the receiver is taken off the hook. As the movable-stop 12 touches the back-stop 29 the circuit is completed over the connection 3^a and the contacts 4—2 of the line-switch, 115 and thence over the selected home-line to the opposite station; where the receiver being on its hook, the circuit is carried over the home-line 33 and the connections 40—41 through which the bell *L* at the call-receiving station is connected into the remaining side of the ringing-battery. On returning the receiver to the hook after use a current 120 from the battery *w* is caused to flow to the coil of the resetting magnet 51 by the pressure of the hook upon the contact-springs 36—38 through which the circuit is closed at that point. The circuit-controller is thus restored to its initial position by the act of hanging up the receiver. This circuit is 130

traced as follows:—from the contact 36 to the connection 46^a over the conductor 37 and through the coils of the resetting magnet 51, to one side of the battery *w* over the conductor 46, the contacts 22—21 and the conductor *v*¹. From the other side of the battery *w* the circuit is carried over the conductors *v*² 41 to the bell, and by the conductor 40 to the other contact 38 at the hook. The magnets 50 and 51 throw the circuit-closer 13 by acting on the rocking-lever 26 to which the arm 13 is connected, as already described. The end of the arm is loosely connected to the end of the lever 26 by a pin 54 on one part and a slot 53 on the other part, so formed and arranged that the movement of the arm 13 takes place in a direction contrary to that of the lever 26. A coiled-spring 55 connected at one end to the arm 13 and at the other end to the lever acts to complete the throw of the arm 13 after the lever 26 has been thrown over the center by the attraction of the magnet.

A swinging shutter 56 rigidly attached to the pivot 25 of the circuit-closer 13, moves with that part in an arc behind a sight-aperture *e*¹ in the case, thereby indicating at all times the position of the circuit-closer, and enabling the user to readily determine the condition of the station, whether he is on, or off, his own line. The magnet 51 of the circuit-closing device is so connected that a current from the battery is caused to flow through it, either by depressing the telephone-hook *h*, or by moving the contact 4 of the line-switch away from its position on any home-line. The proper working condition of the circuits and mechanism at both stations on the circuit requires the circuit-closer 13 at the calling-station to be resting in contact with the stops 17—18, 20—21—22 on the left side, and the corresponding part 13 at the call-receiving station must stand in the opposite position against the stops 15—16—19 on the right.

From the foregoing description it will be evident that the line-switch 4 cannot be disturbed from its position after being set to a selected line, without sending a current through the magnet 51 and thereby setting the arm 13 back to position on the stops 15—16—19. It is not possible, therefore, for a user to place his instrument temporarily in circuit with the home-line of one station by switching and closing his ringing-key to operate the circuit-closer, and then attempt to get the home-line of another station, by moving his line-switch out of position, without going through the same operation of switching and calling; by which operation his own instrument will be disconnected from his line-switch and restored to its initial position.

The diagram Fig. 11 illustrates the position of the circuit-closers at stations 1 and 4

after the line-selecting switch at station 1 has been set to the line of station 4, and the key *m* at the calling-station has been closed; the circuit being completed through the return-conductor *y*. Under these conditions 70 the lever 13 at station 1 is in position against the contacts 17—18, 21—22; and at station No. 4 the corresponding part 13 is in its initial position against its stops 15—16—19. The two stations are then connected in a 75 closed metallic circuit. But should the user at station 1 attempt to move his switch 4 after having set his circuit-controller 13 to operative position by ringing up station No. 4, he will bring the magnet 51 of his controller in circuit with the ringing-battery *w*, through his line-switch. Such movement of the switch thus restores the circuit-controller 13 to its initial position, breaking the connection of the local-circuit with the previously 80 selected line and restoring it to its own home-line. In the event of the line of station No. 4 being "busy," the ringing-circuit will be broken at the stops 36—38, and no 85 current can be obtained either to ring the bell at station No. 4 or to energize the magnet 50 of the circuit-closer at the calling-station No. 1; although any other station not "busy" can be called after the line-switch has been properly set. The primary-circuit 90 of that station will remain therefore on its own line. On the other hand, when conditions are right at both stations, a circuit consisting of the home-line of station No. 4 and the return-conductor *y* and including 95 the primary-circuit at both stations will be completed when the receivers have been taken down, and as soon as the ringing-key of station No. 1 is pressed to call station No. 4. This circuit is traced in the diagram as 100 follows:—from the ringing-stop 12 at station No. 1, which will be resting on its front-stop 10, over the conductors 3^a—35—43, and through the primary 32 of the induction-coil *p* and the transmitter to the hook *h* by the 105 connection 31. With the receiver removed and the hook *h* touching the contact stop 30^a, the circuit is carried over the conductor 30 and the line *y* to station No. 4, where it enters and continues over the connections 30, 110 30^a, *h*, 31, 35 and 37 to the connection 33, taking in the transmitter *t*, the primary of the induction-coil *p* and the battery *B*¹ in the primary-circuit of station No. 4, and so out over the line *x*² to station No. 1. Under this 115 arrangement of lines and conductors, and with the circuit-closer at the calling-station in position, the circuit with the station at the other end will be maintained as long as the line-switch is left undisturbed; but should its contact 4 be moved away from the line already selected, in an attempt to get the line of another station, the contacts 60—61 in the line-switch will close the ringing-battery 120 on the re-setting coil 51 and that part being 125 130

energized will throw the circuit-closer 13 back to its initial position by attracting the armature 28¹. Under such conditions of adjustment when the line-switch at station No. 5 1 is moved in either direction, the contacts 60—61 of the movable switch-piece C will connect the two rings 63—64, and the current from the battery w will flow to the coil of the magnet 51. This circuit will then be 10 traced as follows:—from the contact-plate 64 through the conductors 33^a 33 and 37 to the coils of the magnet 51, which is connected to the conductor 37 at the point 46^a, thence through the coil and the connections 46— 15 22—21 closed on each other through the circuit-closer 24, and out over the line v¹ to the battery w. From the opposite side of that battery the circuit is completed over the line v² to the bell-circuit at station No. 1, 20 where it follows the connections 41—40 and 40^a to the contact-ring 63 in the line-switch. At that point the movable-member 60—61 completes the circuit when it touches any one 25 of the stops 6 on the contact-plate 64, as before described. The switch C, therefore, cannot be moved in either direction without bringing the re-setting magnet 51 in circuit with the battery, and the circuit-controller 13 will be set back to its first position with 30 the result to disconnect the local-circuit from the line to which the switch C has been set and restore the circuit to its own line.

In my Patent, Number 846,889, dated March 12, 1907, I have shown a telephone 35 system having some features in common with that herein illustrated and described, in which the circuit-controlling device is operated mechanically by means so connecting it with the movable-stop of the ringing-key that whenever that part is actuated to close 40 the calling-circuit it will operate the bell at the opposite station, and also complete the connection of the local-circuit with the line. in the present invention the primary-circuit 45 is controlled electrically, with certain advantages in the operation which insure a closed and practically isolated circuit.

Referring to Figs. 2, 3, 4, 5 and 5^a more 50 particularly, it will be noticed that the stationary-contacts alternate with intermediate blank-stops (2^x) arranged at uniform 55 distances apart around the circle. The use of these intermediate stops in a switch having no locking or controlling means, such as a ratchet and pawl, and particularly where the switch contains a large number of line-contacts, is of advantage in serving to prevent short-circuiting of two lines by the accidental placing of the movable-contact in 60 such position that it will rest on two line-contacts at the same moment.

Among other novel features in this switching mechanism, attention is called to the combination with the line-switch 65 through which the lines of different sta-

tions are selected at will, of the circuit-closing means that operates to control the connection of the local circuit either with the line individual to the station, or with the line-switch, according to the adjustment of such circuit-closer. One advantage of this arrangement is that the user at any station may keep his line-switch set to any particular line continually, where he may desire to call up the same station at frequent intervals without stopping to set his line-switch every time he wishes to communicate with that station. Without disturbing his line-switch, therefore, after once adjusting it to the required line, the user at such station has only to remove his receiver from the hook and close the ringing-key in order to put his station on the line and then by returning the receiver to place he is restored to his own line; thereby placing his station in condition to be called and communication had with him from any other station. Through the adjustment of the movable-member of the line-switch selection is made of the desired line or conductor; and by operating the circuit-closing means the local lines or conductors of the station are connected into or with the selected line.

Having thus described my invention, what I claim and desire to secure by Letters Patent is:—

1. In a telephone system the combination with stations having each a home-line, a primary-circuit and a source of current for said circuit, of a line-selecting switch 100 containing a terminal for the home-line of each connected station, a movable-contact therefor, a ringing-circuit including a ringing-key, means connecting the ringing-key with the movable-contact whereby the selected home-line becomes an element of the ringing-circuit on operating the ringing-key of the selecting station, and circuit-connecting means actuated by the ringing-current as that circuit is closed at the selecting-station through the ringing-key, and operating to connect the primary-circuit into the line-selecting switch of the station. 110

2. In a telephone system, the combination with line-circuits comprising a home-line 115 for each station and a return-conductor common to a plurality of stations, a primary-circuit at each station including a source of current, and a line-selecting switch; of a circuit-connecting device normally connecting the primary-circuit of the station with its source of current through its home-line, and adapted by adjustment to cut out the home-line and connect its primary-circuit into the line-selecting switch, 120 a ringing-circuit having circuit-closing means at each station operating to transmit a ringing-current over the home-line to which the line-selecting switch of the station is set, means operated by the same cur- 125

- rent through the movement of the ringing-key for actuating the circuit-connecting device of the station when acting as a selecting-station to complete the line-circuit with 5 a selected station, and means actuated electrically by the next movement of the line-selecting device after the ringing-key has been operated to restore the primary-circuit to its home-line.
- 10 3. In a telephone system, the combination with stations having each a primary-circuit, of line-circuits containing a separate home-line for each station, a local source of current therein, a line-selecting switch provided with a separate terminal for the home-line of every connected station, means connecting the primary-circuit of the station into its own home-line and source of current, means for completing a ringing-circuit through the line-selecting switch and the selected home-line to the station on said line including a circuit-closing key, means actuated by the current on said circuit for disconnecting the primary-circuit from its 20 own source of current and connecting in circuit with the source of current of the selected station, and means actuated by the movement of the line-selecting switch away from the selected home-line for opening the line-circuit and restoring the primary-circuit to its own source of current.
4. In a telephone system, the combination of primary-circuits, line-circuits having a separate line for each primary-circuit, a 35 source of current therein and with which the primary-circuit is normally connected, a line-selecting device controlling the connection between a primary-circuit and the line of every other primary-circuit but its own, means for transmitting a calling-current over a selected line, electrically actuated circuit-connecting means operating at the moment of closing the calling-circuit to connect the primary-circuit at the transmitting end 40 into the selected home-line, and means controlling said circuit-connecting means from the line-selecting device whereby a change in the adjustment of the said device from a selected line after the transmission of the 45 calling-current will open the line and restore the normal condition of the primary-circuit.
5. In a telephone system, stations having each a primary-circuit and a source of current, line-circuits including a home-line to each station and a line-switch containing switch-contacts for all the home-lines excepting the line of the station itself and a movable-contact through the adjustment of 55 which the primary-circuit is connectible at will to the home-line of a selected station, a ringing-circuit including a ringing-key, means controlled through the ringing-circuit and operating when the ringing-key is 60 moved to cut off the primary-circuit from its

own home-line and connect it with the selected home-line, and means controlled through the movable-contact of the line-switch and operating to disconnect the primary-circuit from said selected line and restore it to its own line by the act of moving said contact out of position after transmitting a ringing-current over the completed circuit. 70

6. In a telephone system, line-circuits for 75 a plurality of stations having a home-line for each station, a source of current with which the primary-circuit of each station is connected through the home-line of the station, a line-selecting switch having a movable member operating to control the connection of the primary-circuit with every home-line but its own, calling-circuits including an electrically-actuated calling-device at each station normally on its home-line, electrically actuated circuit-connecting means for disconnecting the primary-circuit from its home-line and simultaneously connecting it with the selected line, said means being actuated by the calling-circuit, and means controlled by the movable-member of the switch operating to restore the primary-circuit to its normal condition on its home-line when the movable-member of the switch is moved out of position. 95

7. In a telephone system the combination, with a plurality of line-circuits having a home-line for each station and a source of current for the primary-circuit connected therewith through the home-line, a plurality 100 of calling-circuits including an electrically-actuated calling-device and a circuit-closing key at each station; of electrically operated circuit-connecting means in the calling-circuit between the circuit-closing key and the 105 source of calling-current acting to cut off the primary-circuit from its own home-line and source of current at the time of closing the calling-circuit at the circuit-closing key to call another station, and a line-selecting 110 switch for connecting the said home-line into the home-line of the station to be called, said switch having two series of stationary-contacts and two movable-contacts, one of 115 said series of stationary-contacts and its associated movable-contact being adapted to select and individually connect the home-line of every other station into the primary-circuit of the station at which the operated switch is situated, and the stationary-contacts and movable-contacts comprising the 120 other series being arranged in alternate position with reference to the corresponding contacts in the first-named series, and operating to close the circuit on the circuit-connecting means and thereby return the same to its normal position connecting the primary circuit to its own home-line through the movement of the line-selecting switch 125 out of position. 130

8. In a telephone system a normally open line-circuit to each station comprising a line peculiar to each station and a return-conductor, a primary-circuit at each station 5 normally connected into the line of the station and connectible into the return-conductor at will, a line-selecting switch, an electrically operated circuit-controlling device between the primary-circuit and the 10 line, for connecting the said circuit to the line, a normally open calling-circuit to each station, in which one side is formed of the line of the station, a circuit-closing key in 15 said circuit, means operatively connecting the circuit-controlling device in circuit with the calling-circuit key, arranged to operate the circuit-controlling device by the act of sending a calling-current over the line, and means operating to return the primary-circuit 20 to its line when the line-selecting switch is moved away from the selected line.

9. In a telephone system, a selecting-switch at each station comprising a circular series of stationary line-contacts and a rotatable contact movable at will in either direction around the circle of line-contacts; in combination with a home-line for each station adapted to form one side of a call receiving and sending circuit with another 30 selected station, a circuit-controlling device normally connecting the home-line into the primary-circuit of its station, said home-line being provided with a terminal in the selecting-switches of all the other stations, 35 electrically actuated means for operating the circuit-controlling device when the movable-contact of the switch is placed on a selected line-contact, and means operating to restore the primary-circuit to its home-line 40 by the act of moving the switch away from the selected line-contact in either direction.

10. In a telephone system, a plurality of line-circuits comprising a home-line for each station and a return-conductor, a line-selecting switch at each station having terminals 45 for the home-lines of the other stations, calling-circuits including a source of calling-current, a calling-device at each station between one side of said source of current and the home-line of the station, a circuit-closing key in open circuit between the line-selecting switch and the remaining side of the 53 source of calling-current, and an electrically actuated circuit-controlling device in said circuit between the key and the source of current comprising a series of circuit-closing stops located between the local circuit of the station and its home-line, a second series of similar stops located between said 55 local circuit and the line-selecting switch, and a circuit-controlling member movable between said series of stops, and electrically actuated means operating on the completion of a calling-circuit by its circuit-closing key 60 to set the movable-member against one series 65 of stops, and under the movement of the line-selecting switch out of position to set said movable-member against the other series of stops.

11. In a telephone system with a plurality 70 of stations, the combination of line-circuits, a line-selecting switch at each station containing terminals for all the lines from the other stations, calling-circuits including an electrically actuated calling-means at each 75 station connected into one side of a source of calling-current, and connectible into its own line, means for completing a calling-circuit from the other side of the source of current over the line of a selected station through 80 the line-selecting switch, electrically operated circuit-controlling means operating to disconnect the local circuit of the station from its own line and connect it with the selected line by the act of completing a calling-circuit, and means operating to restore the station to its own line by the act of moving the line-selecting switch out of position.

12. In combination a talking line, a local talking-circuit including receiving and 90 transmitting telephone instruments, an electrically operated circuit-closing device controlling the connection thereof with a talking-line, and normally holding the same in disconnected relation thereto, a calling-circuit 95 including a circuit-closing key, means for operating the circuit-closing device of the talking-circuit by the act of closing the calling-circuit, and means arranged to throw off the talking-circuit closing device and 100 thereby disconnect the local circuit from the line by the act of hanging up the receiving telephone instrument.

13. In combination a plurality of line-conductors, a selecting-switch adapted to 105 form different metallic circuits therefrom, a circuit-closing device by the operation of which a local circuit is connected into or is disconnected from the selected conductors, and electrically operated means for operating the circuit-closing device including a setting magnet in open circuit with a source of current, means for closing said circuit, a resetting magnet also in open circuit with 110 said source of current, and means for closing a circuit through the resetting magnet by the act of returning the receiver to the telephone hook.

14. In a telephone system, the combination with stations provided with telephone 120 instruments and calling devices, of lines connecting the several stations, a selecting switch at each station for putting the station into connection with any other desired station in the system, means for completing 125 a calling circuit through the line-selecting switch and the station to be called, and means actuated by the current of the calling circuit for disconnecting the telephone instruments of the calling station from the 130

individual line wire of that station and at the same time putting it into circuit relations for talking with the line of the called station, substantially as set forth.

- 5 15. In a telephone system, the combination with stations provided with telephone instruments and calling devices, of lines connecting the several stations, a selecting switch at each station, means for completing a calling circuit through the selecting switch and the station to be called, means operating when the circuit is completed for putting the telephone instruments of the calling station into circuit relations for talking, and electrically actuated means for positively cutting out the telephone instruments of the station and restoring them to normal conditions connected with their individual line should the line-selecting switch be moved after a call had been made and before the telephone instruments are hung up, substantially as set forth.
- 10 16. In a telephone system, the combination with stations provided with telephone instruments and calling devices, of individual lines connecting the several stations and a common return, a selecting switch at each station for putting the station into connection with any other desired one of the system, means for completing a calling circuit through the line selecting switch and the station to be called, means for connecting the telephone instruments of the calling station with the common return line when the system is to be used, and means actuated by the current of the calling circuit for connecting the telephone instruments of the calling station with the line with which the selecting switch has made contact.
- 15 17. In a telephone system, the combination with stations provided with telephone instruments and calling devices, of individual lines connecting the several stations, a selecting switch at each station for putting the station into connection with any one of the incoming individual lines, a return conductor common to all the stations, means for completing a calling circuit through the line selecting switch and the station to be called, means for connecting the telephone instruments with the return conductor when they are to be used, and electrically operated means actuated by the current of the calling circuit for connecting the telephone instruments of the calling station with the line with which the selecting switch has been connected.
- 20 18. In a telephone system, the combination with stations provided with telephone instruments and calling devices, of individual lines connecting the several stations, a selecting switch at each station for putting the station into connection with any other desired one in the system, means for completing a calling circuit through the line-selecting switch and the station being called, and a single means actuated by the current of the calling circuit for connecting the telephone instruments of the calling station with the line-selecting switch, whereby such instruments are connected and put into talking relation with the called station.

In testimony whereof I have hereunto set my name to this specification in the presence of two subscribing witnesses.

ALBERT KOCH ANDRIANO.
